UNITED STATES PATENT OFFICE

2,541,537

UNDERCUTTER

George W. Newcomb, Baltimore, Md.

Application July 22, 1946, Serial No. 685,444

2 Claims. (Cl. 145—124)

1

This invention relates to a socket cutter, and it is one object of the invention to provide a cutter by means of which sockets may be formed in furniture and the like to receive ends of dowel pins, chair rounds, bars, and the like, the socket being so cut that it increases in diameter towards its inner end, and thus allows the end of a dowel pin driven into the socket to be spread by a wedge deposited in the socket and firmly held against dislodgement from the socket.

Another object of the invention is to provide an under-reamer with cutters which are normally in a retracted position allowing the under-reamer to cut its way into the wall of a previously bored hole in a chair leg or the like and form a socket, means being provided for guiding the cutters outwardly and enlarging the socket after the hole has been cut to a predetermined depth.

Another object of the invention is to provide an under-reamer with cutters which are slidably longitudinally of the under-reamer in grooves formed therein, lower portions of the grooves having sloping surfaces acting as cams for guiding the cutters outwardly when the cutters are forced downwardly.

Another object of the invention is to provide actuating means for expelling the cutters consisting of a collar loosely mounted about the under-reamer, and yieldably held in a raised position by a spring which maintains the collar in contact with cams of a lever pivoted to a second collar. It will thus be seen that after a socket has been started, the lever may be swung downwardly, and the cams will apply pressure to force the cutters outwardly.

Another object of the invention is to provide an under-reamer having socket enlarging means associated with it, which is of simple construction and easy to operate.

The invention is illustrated in the accompanying drawings wherein:

Figure 1 is a side view of the improved drill with the auxiliary cutters in a retracted position;

Figure 2 is a side view showing the auxiliary cutters extended to form a socket gradually increased in diameter toward the inner end;

Figure 3 is a fragmentary view showing a cam of modified formation;

Figure 4 is a view looking at the lower end of the under-reamer with the auxiliary cutters retracted;

Figure 5 is a view similar to Figure 4 showing the auxiliary cutters extended;

2

Figure 6 is a view showing the under-reamer in longitudinal section with the auxiliary cutters retracted;

Figure 7 is a view similar to Figure 6 showing the auxiliary cutters extended;

Figure 8 is a sectional view taken along line 8—8 of Figure 7;

Figure 9 is a sectional view taken along line 9—9 of Figure 6;

10 Figure 10 is a sectional view taken along line 10—10 of Figure 6;

Figure 11 is a side view of an end portion of a dowel;

Figure 12 is an end view of the dowel;

15 Figure 13 is a view showing the dowel fitted into a socket and its inserted end expanded;

Figure 14 is a view taken along line 14—14 of Figure 13;

20 Figure 15 is a view of a wedge by means of which the dowel pin is spread.

The improved under-reamer constituting the subject matter of this invention is used for cutting sockets to receive dowel pins, chair rounds, or the like. When a drill of conventional construction is used, a socket is formed which is of an even diameter throughout its depth, and even if a wedge is placed in the socket to spread the end of a dowel pin or round, a permanent mounting will not be obtained, as the dowel pin may work loose and slip out of the socket.

25 The under-reamer 1 may be of any desired length and diameter, and when in use is mounted in a drill chuck 2. The lower end of the under-reamer may be formed with cutting teeth or the under-reamer sharpened in any manner desired so that when the under-reamer is turned in a previously bored hole A, a socket 3 will be formed in a board, chair leg, or the like 4. Grooves 5 extend longitudinally of the under-reamer and

30 each has its lower end portion gradually decreased in depth to form a cam surface 6 extending downwardly at an outward incline as shown in Figures 6 and 7. Auxiliary cutters 9 are slidably mounted in the grooves or recesses 5, and

35 each cutter has its lower portion 9 extending downwardly at an outward incline and its upper end formed with an outwardly extending finger 11. The fingers 11 engage in sockets 12 formed in a collar 13 which fits loosely about the under-reamer and is slidable along the under-reamer from the raised position shown in Figure 6 to the lowered or depressed position shown in Figure 7.

40 A second collar 14 fits about the under-reamer, where it is secured in predetermined spaced relation to the lower end thereof, and upon this

45 50 55

collar rests the lower end of a helical spring 15 which has its upper end bearing against the under surface of the collar 13 so that the collar 13 will be urged upwardly to the raised position. Spaced upwardly from collar 13 is a ring or collar 16 secured by a pin 17 which passes transversely through the under-reamer, and between the ring 16 and the collar 13 is a sleeve 18. The sleeve 18 is free upon the under-reamer, and carries pins 19 which pass through the forks or arms 20 of a lever 21 and pivotally mount the lever. Cams 22 project from the arms of the lever or handle 21 and the curved lower edge faces of the cams bear against the upper surface of a wear ring or disk 23 which rests upon the collar 13. When the handle is swung downwardly, the collar 13 will be moved downwardly with it, and as the collar moves downwardly, the cutters 8 will be shifted downwardly in the grooves 5 and their lower ends gradually shifted outwardly by the cam surfaces 6. Therefore, after a socket has been cut to a desired depth, the auxiliary cutters may be gradually moved outwardly and a socket will be formed of gradually increasing diameter toward its inner end. A dowel pin or chair round 24 formed with crossed slits 25 leading from its end will be driven into a socket after a cross-shaped wedge 26 has been deposited in the socket, and as the arms of the wedge enter the slits 25, the dowel pin or round will be spread and firmly anchored in the tapered socket as shown in Figure 13. Instead of providing arms of the handle 21 with cams 22, cams 27 of substantially elliptical or oval shape may be mounted upon end portions of the pins 19 inwardly of the arms of the lever or fixedly secured to the lever arms to turn therewith. Such cam plates are shown in Figure 3, and referring to this Figure, it will be seen that bearing balls 24 may be provided between the disk 23 and the collar 13, and thus form a bearing for the collar. A similar bearing is provided above the cam plates and consists of a disk 25 and bearing balls 26. With an under-reamer of the improved construction, sockets may be quickly cut and be either of an even diameter or tapered toward their outer ends so that dowel pins driven into the sockets will be wedged in the sockets and very firmly held against displacement from the sockets.

Having thus described the invention, what is claimed is:

1. An under-reamer comprising a substantially cylindrical shank formed with longitudinally extending grooves spaced from each other circumferentially of the shank, and having their lower end portions gradually decreased in depth to provide cam surfaces extending downwardly at an outward incline, cutters having cutting edges slideable longitudinally in said grooves and having their lower portions extending at an outward incline, fingers extending from upper ends of said cutters and projecting radially from the shank, a collar loose about said shank and formed with sockets into which the fingers fit to connect the cutters with the collar, a second collar secured about the lower end portion of the shank adjacent to the upper edge of the cam

surface of the grooves and engaging the edge surface of the cutters whereby to cam them inwardly as they are moved upwardly on the shank, a helical spring surrounding the shank between the collars and urging the first collar upwardly to a raised position for holding the cutters retracted, a ring secured about said shank above the first collar, a sleeve fitting loosely about the shank between the first collar and said ring, pins projecting from opposite sides of said sleeve, a lever having arms at its lower end pivoted upon said pins, and cam members extending from said arms and having curved lower edges engaging the first collar for forcing the same downwardly and cause the cutters to be shifted downwardly in the grooves and gradually moved outwardly to an extended position by engagement with the cam surfaces at lower ends of the grooves and the depth of the grooves being so that the cutters will not project beyond the shank in their uppermost position but will project beyond the shank in their lowermost cutting position.

2. An under-reamer comprising a substantially cylindrical shank formed with longitudinally extending grooves, having lower portions provided with outwardly sloping cam surfaces, cutters having cutting edges slideable longitudinally in said grooves and having lower end portions extending outwardly at an incline, and moved to an extended position by engagement with the cam surfaces when the cutters are shifted downwardly in the grooves, and the depth of the grooves being so that the cutters will not project beyond the shank in their uppermost position but will project beyond the shank in their lowermost position an abutment about the lower portion of said shank adjacent to the upper edge of the cam surfaces of the grooves and engaging the edge surface of the cutters whereby to cam them inwardly as they are moved upwardly on the shank, a collar loose about the shank above the abutment, a spring about the shank between the abutment and the collar and urging the collar upwardly, said cutters having their upper ends connected with the collar and being held in a retracted position when the collar is in its raised position, a ring secured about the shank above the collar, a sleeve about the shank between the collar and the ring, and a lever having arms pivoted to opposite sides of the sleeve and provided with cams acting upon the collar to force the collar downwardly and shift the cutters to an extended position when the lever is swung downwardly.
